UNITED STATES PATENT OFFICE.

JOHN T. BEECHLYN, OF LYNN, MASSACHUSETTS, ASSIGNOR TO GENERAL ELECTRIC COMPANY, A CORPORATION OF NEW YORK.

SWITCH.

1,192,732.

Specification of Letters Patent. Patented July 25, 1916.

Application filed December 4, 1915. Serial No. 65,117.

To all whom it may concern:

Be it known that I, JOHN T. BEECHLYN, a citizen of the United States, residing at Lynn, county of Essex, State of Massachusetts, have invented certain new and useful Improvements in Switches, of which the following is a specification.

My invention relates to switches for household lighting and other purposes, and it is more especially concerned with causing actual movement of the switch proper to be delayed more or less after the action of the operator to bring it about. This result can be obtained by opposing a gradually yielding resistance to movement of the actuating member or device of the switch mechanism proper and at the same time providing an additional actuating member or device and means initially controlled thereby for exerting on the first actuating member an automatically sustained force such as will gradually overcome the aforesaid resistance and bring about the desired movement of the switch. By arranging that an actuating force shall be thus imposed and resisted only when the switch is to be opened, it is possible to have the closing of the switch take place in the ordinary undelayed manner, which is generally more convenient than a delayed closing.

I have herein illustrated and described mechanism embodying my invention as applied to a quarter-turn rotary snap switch. While, however, this mechanism is the best for my purpose at present known to me, and while the invention extends to its specific features and details of operation and construction and combinations and arrangements of parts, yet the invention is not confined thereto,—its scope being indicated in my claims.

In the accompanying drawing, Figure 1 is a front view of a wall switch device constructed in accordance with my invention, certain outer parts being partly broken away and removed to reveal those behind them. Fig. 2 is a vertical mid-sectional view at right angles to Fig. 1. Fig. 3 is a horizontal fragmentary mid-sectional view on an enlarged scale. Fig. 4 is a rear view, certain parts being in section at a plane indicated by the line 4—4 in Fig. 2. Fig. 5 is an inclined schematic view of the principal operating parts, some of them being dis-

placed from their normal positions or 55 merely indicated in dotted outline, etc., for clearness of illustration. Fig. 6 shows an enlarged section taken at a plane corresponding to the line 6—6 in Fig. 3, as seen from the left. Fig. 7 is a view from the right of a plane of section indicated by the line 7—7 in Fig. 3. Fig. 8 is a view from the right of a plane of section indicated by the line 8—8 in Fig. 3. Fig. 9 is a fragmentary view similar to Fig. 5, but illustrating a modification. Fig. 10 is a fragmentary end view showing the operative relations of some of the parts shown in Fig. 9.

Referring to Figs. 1, 2, 3 and 6, it will be seen that the switch mechanism is inclosed in a casing structure 11 of porcelain, bisque, or other insulating material, and that this casing 11 is secured in place in the wall in any approved or preferred manner. A plate 12 is secured to the front of the casing 11, 70 by means of screws, and the usual exterior front plate is similarly secured to the plate 12. An opening 13 in the front plate gives a view of the "on" and "off" signs of an indicator disk 14 which is secured to the rear 75 end of a metal sleeve 15 molded or otherwise secured in the operating handle 16. The handle 16 is secured to the disk-like metal actuating member 17 (by whose movement the whole switch device is controlled) 80 by means of springy axially extending lugs 18 that engage in shallow internal grooves 19 in said sleeve 15.

Referring to the switch mechanism proper, it will be seen from Figs. 1, 2, 3 and 90 4 that there is a rotary shaft 20 having an extended bearing in a metal sleeve 21 secured in the rear wall of the casing 11, and that a four toothed or shouldered ratchet disk 22 is secured against the rear wall of 95 the casing by pins that extend into holes in a metal plate 23 riveted in place by the sleeve 21 and engaged with said rear wall so that it cannot turn. Loose on the shaft 20 is a metal switch plate 24 having its side 100 edges bent to form a guideway at its rear side, and in this guideway slides a flat catch 25 having a rearward projection 26 for engaging the teeth of the ratchet disk 22. On the front of the switch plate 24 is insu- 105 latively mounted the switch proper, consisting of blades or pole-pieces 27 for engaging contacts 28 which are secured in the casing

11 in any approved manner and provided with binding screws 29 for the connection of the current leads. As the particular switch shown is of the double pole type, the switch proper comprises two pair of insulatively supported pole-pieces (and corresponding contacts) arranged 90° apart. A cam or eccentric 30 secured to the shaft 20 so as to turn with it works in a transverse slot in the catch 25 and acts to move said catch cross-wise of the shaft. The switch plate 24 is operatively connected to the shaft 20 by means of a left-hand helical spring 31 coiled about said shaft and having its ends secured to a lug 32 on said switch plate and in a notch 33 in a disk member 34 which is itself keyed fast to said shaft. The shaft 20 (with the disk 34) constitutes the direct actuating member of the quarter turn rotary snap switch mechanism just described; for by turning it clockwise 90° at a time the switch will be stepped around with a quick movement 90° at a time, in a readily understood manner, alternately opening and closing the circuit.

Referring, now, to Figs. 2, 3, 4 and 5, it will be seen that the means shown for opposing a gradually yielding resistance to movement of the actuating member 20 comprises a dash-pot device and a sort of lost motion connection therefrom to the shaft. The dash-pot device comprises a pair of pistons or plungers 35 and working in flanged metal cylinders 36 which are mounted in trough-like recesses at the rear side of the casing structure 11 with their flanges in grooves in the trough walls and are held in place and prevented from turning by a metal back-plate secured to said casing structure by rods 11'. The lost motion connection comprises a crank 37 fast on the rear end of the shaft 20 and a sheet metal yoke piece 38 in whose peculiar shaped opening works the flat "crank pin" 39. The yoke 38 is free to reciprocate with the pistons 35, and its lateral projections slide against ways on the casing structure which keep it from turning out of the plane in which it is shown.

From Figs. 4 and 5 it will be seen that when the shaft 20 and crank 37 revolve as indicated by the arrows (*i. e.*, clockwise) from the dotted line position of Fig. 4 (which corresponds to the full line position of Fig. 5), the crank pin 39 will turn about 90° against the curved upper edge of the opening in the yoke 38 without moving the yoke or the dash-pot pistons 35; that then said crank pin will engage the lower edge of the yoke notch 41 and gradually force the yoke downward against the resistance of the pistons, this action lasting about 90° more; that when the yoke 38 has thus been forced down far enough the crank-pin 39 will override the lower corner of said notch 41 and travel the next 90° against the lower

edge of the yoke opening; and that thereafter said crank-pin 39 will enter the notch 43 and gradually restore the yoke 38 to its original position. It will also be understood that the two periods of unresisted movement or lost motion in the 360° cycle above described concur with closing actuations of the snap switch mechanism, and that the periods of resisted movement concur with opening actuations of the switch mechanism, so that only the opening will be delayed after the action of the operator that brings it about.

Referring, now, to Figs. 3, 5, 6 and 7 it will be seen that the actuating member 17 already referred to is operatively connected to the shaft-actuating member 20 of the switch mechanism proper by means of a left-hand helical spring 45, coiled about the shaft and having one end secured in the notch 33 of the disk 34 and the other in a hole 47 in the central disk portion of said member 17. Around the spring 45 is a sleeve or barrel 50 which has at its forward end tongues 51 that engage in peripheral notches 52 in the disk portion of said actuating member 17 and at its rear end a flange 55 that is peripherally shouldered so as to act as a four toothed ratchet; and at the rear side of the plate 12 (between which and the disk 34 the ratchet flange lies) is pivoted a spring-pressed pawl 56 for engaging the ratchet 55 to prevent reverse movement of said member 16 by said spring 45 when once said spring 45 has been sufficiently stressed. This spring and ratchet mechanism serves as a means for exerting and imposing on the actuating member 20 an automatically sustained force such as will ultimately cause operation of the switch mechanism, as will be fully explained. In order that the spring 45 may be tensioned without turning the actuating member 20, a lost motion connection between the actuating members 17 and 20 is provided,—that shown, comprising a disk-like piece 57 secured on the tapped and flattened end of the shaft 20 by a screw 58 and having peripheral lugs 59 that engage the tongues 51 of the sleeve 50, as shown in Fig. 6 and so serve to maintain the spring 45 under suitable initial tension.

When the actuating member 17 is turned clockwise one ratchet tooth (90°) by means of the handle 16, the spring means 45 is stressed or wound up so as to exert on the actuating member 20 a force tending to turn said actuating member clockwise so as to cause operation of the switch proper. If the switch should at this time be open, the stress so produced in the spring 45 will be freely transmitted to the spring 31 and immediately equalized between these springs, and the switch mechanism proper will be caused to operate almost as though the handle 16 were directly secured to its actuating

member 20; but if the switch should be closed, the stress will be maintained in the spring 45 by means of the ratchet mechanism 55, 56, and the relative immovability 5 of member 20. The spring will thus be kept in action while the dash-pot resistance is being gradually overcome and spring 31 gradually tensioned until the shaft 20 has moved to the point of operating the release 10 device 22, 25 of the switch mechanism proper. As a result, the opening of the switch will be delayed over a period determined by the relative characteristics and adjustment of the springs 31 and 45 and the 15 dash-pot device, etc.

It will be seen that my switch device is for many purposes adapted to replace the two-switch three-way arrangement commonly used when the light is to be turned on at one 20 point or floor when entering a room or a hallway and turned off at another point or floor when leaving it, for it allows one to actuate the switch to extinguish the light and then traverse and leave the room or 25 stairway before the extinguishment occurs.

In order to prevent a careless person from leaving the lights burning behind him, however, the switch above described may be modified as shown in Fig. 9. As here shown, 30 the ratchet element 65 (corresponding to the ratchet 55) has just two teeth 66 and 67 (the latter wider than the former) for coöperating with the pawl 56, and the actuating member 17 is turned 180 degrees each time 35 instead of 90 so as to stress the spring 45 for first closing and then opening the switch. To insure that it shall be operated in this way, provision is made for preventing operation of the actuating shaft member 20 until a full 40 180 degree turn has been given the actuating member 17. For this purpose, the plate 72 (corresponding to the plate 12) is provided with a double toothed ratchet flange 73, and a coöperating outwardly acting spring actuated pawl 76 is pivoted to the one armed part 84 (corresponding to the disk 34). This pawl 76 is so located that the narrow ratchet tooth 66 passes to one side of it, but that the wide tooth 67 of the ratchet 65 acts 45 on its inner end as a releasing cam,—the design and adjustment being such that the release occurs each time just after a tooth of said ratchet 65 has tripped past its pawl 56. In order that the actuating member 17 may 50 turn 180 degrees relative to the shaft 20, the part 87 (corresponding to the part 57) is made with but a single lug 89 (corresponding to the lug 59), and only a single tongue 91 (corresponding to a tongue 51) is made 55 long enough to project past the disk portion of the actuating member 17 into its path.

What I claim as new and desire to secure by Letters Patent of the United States, is,—

1. A switch device comprising a switch 60 mechanism having an actuating member,

means opposing a gradually yielding resistance to movement of said member to actuate said switch mechanism, an additional actuating member, and means controlled by said latter actuating member for exerting and imposing upon said first-mentioned actuating member force sufficient to gradually overcome the aforesaid resistance and move said first-mentioned member to actuate said switch mechanism. 70

2. A switch device comprising a switch mechanism having an actuating member, means opposing a gradually yielding resistance to movement of said member to cause opening of the switch, but unresisting to 80 movement of said member to cause closing thereof, an additional actuating member and means controlled thereby for exerting on said first-mentioned actuating member force sufficient to gradually overcome the aforesaid resistance and move said first-mentioned member, and means for maintaining said latter means in action when once rendered capable of causing ultimate opening of the switch. 85

3. A switch device comprising a switch mechanism having an actuating member, means opposing a gradually yielding resistance to movement of said member to actuate said switch mechanism, an additional actuating member and a spring connection therefrom to said first-mentioned actuating member adapted when stressed gradually to overcome the aforesaid resistance and move said first-mentioned actuating member, and means for preventing reverse movement of said additional actuating member by said spring connection. 95

4. A switch device comprising a snap switch mechanism having a rotary actuating member, means opposing a gradually yielding resistance to movement of said member to actuate said switch mechanism, an additional rotary actuating member and a spring connection therefrom to said first-mentioned actuating member adapted when stressed gradually to overcome the aforesaid resistance and rotate said first-mentioned actuating member, and ratchet mechanism for preventing reverse movement of said additional actuating member by said spring connection when the latter has been stressed sufficiently to cause ultimate operation of said switch mechanism. 100

5. A switch device comprising a snap switch mechanism having a rotary actuating member, an operating spring, and a release device, movement resisting means associated with said actuating member and including a dash-pot device operatively connected thereto by a lost motion connection so as to oppose movement thereof to cause opening of the switch, but not movement thereof to cause closing of the switch, an additional rotary actuating member and a 115 120 125 130

spring connection therefrom to said first-mentioned member adapted when stressed to overcome the dash-pot resistance and rotate said first-mentioned actuating member so as 5 to stress the aforesaid actuating spring, and ratchet mechanism for preventing reverse movement of said additional actuating mem-

ber by said spring connection when the latter has been stressed sufficiently to cause ultimate operation of said release device. 10

In witness whereof, I have hereunto set my hand this second day of December, 1915.

JOHN T. BEECHLYN.
